(57) **CLAIM**

The ornamental design for a seat base striker plug, as shown and described.

DESCRIPTION

FIG. 1 is a top, perspective view of a seat base striker plug shown in its environmental use according to the present design;

FIG. 2 is a second top, perspective view thereof;

FIG. 3. is a bottom perspective view thereof;

FIG. 4 is a top view thereof;

FIG. 5 is a bottom view thereof;

FIG. 6 is a left side view thereof;

FIG. 7 is a right side view thereof;

FIG. 8 is a front view thereof; and,

FIG. 9 is a rear view thereof.

The broken line representations in FIG. 1 illustrate environmental structure and in FIGS. 2-3 and 5-9 depict portions of the seat base striker plug which form no part of the claimed design.
